REVOLVER CRANE LOCK

William L. Swartz, West Hartford, Conn., assignor to Colt's Patent Fire Arms Manufacturing Company, Hartford, Conn., a corporation of Connecticut

Application April 28, 1943, Serial No. 484,803

10 Claims. (Cl. 42—62)

This invention relates to improvements in a revolver crane lock mechanism comprising a latch and operating means therefor.

In a conventional revolver, one end of the crane is pivotally supported by an arbor rotatably mounted in a seat in the frame of the revolver. The cylinder is rotatably mounted on an arbor mounted on the outer or free end of said crane. When the cylinder is disposed in operative position in the opening provided therefor in the frame, the rearward end of said cylinder is maintained in said operative position therein by a cylinder latch or lock.

Should the revolver be accidentally dropped so that the projecting portion of the cylinder exposed on the side of the frame opposite the crane strikes a hard surface such as a floor, such a blow against the cylinder may, if sufficiently great, spring or distort the crane and cylinder carrying arbor thereof to such an extent that the chambers of the cylinder would no longer be in proper alignment with the barrel.

A number of different types of crane latches have heretofore been developed, said latches being for the purpose of preventing distortion of the crane under conditions such as referred to in the foregoing.

The present invention represents an improvement over said prior constructions and it is one object of the invention to provide a crane latch which is connected to the crane in such a way as to render the latch more mechanically efficient than those heretofore developed.

It is another object of the invention to produce a crane latch and actuating mechanism which are, for the most part, concealed within the revolver construction when all parts thereof are disposed in operative firing positions, whereby substantially no objectionable projections are presented by the crane latch and/or actuating means therefor.

A still further object of the invention is to provide a crane latch which projects outward from the free end of the crane and coengages with a latch receiving notch in the frame of the revolver.

Another further object of the invention is to provide a crane latch and actuating mechanism therefor wherein no cavities or recesses are exposed on the exterior of the revolver when all parts are disposed in operative position, whereby no accumulation of dirt or extraneous material will occur to foul the functioning of the crane latch and its actuating mechanism.

Other objects of the invention and the details

thereof will be described in the following specification and illustrated in the accompanying drawing forming a part thereof.

The accompanying drawing shows the embodiment of the invention which is deemed preferable, but it will be understood that the drawing is intended for illustrative purposes only and is not to be construed as defining or limiting the scope of the invention, the claims forming a part of this specification being relied upon for that purpose.

In the drawing,

Fig. 1 is a side elevation of a revolver having all parts in operative position for firing and embodying the present invention.

Fig. 2 is a fragmentary front elevation of the revolver shown in Fig. 1 but being on a larger scale than that illustrated in Fig. 1.

Fig. 3 is a view similar to Fig. 2 but showing the cylinder and crane moved to inoperative position for purposes of removing cartridge shells from the cylinder or loading cartridges therein.

Fig. 4 shows two side views and one edge view of the crane latch per se.

Fig. 5 is a fragmentary, partially sectioned, side elevation of the crane per se.

Fig. 6 is a side elevation similar to Fig. 5 but showing the crane latch and operating mechanism therefor assembled in operative position.

Fig. 7 is a side elevation of a pin for limiting the movement of the latch outward of the crane.

Fig. 8 is a side elevation of a spring for actuating the crane latch operating plunger.

Fig. 9 is a plan view of the crane latch operating plunger.

Fig. 10 is a side view, partly in section, of the crane latch operating plunger.

Referring to Fig. 1, the revolver to which the present invention is applicable, though not restrictively so, comprises a frame 10 having a handle 12 formed thereon at one end and a barrel 14 secured thereto at the other end. The frame 10 is provided with a generally rectangular recess or opening 16 disposed rearward of the rear end of the barrel 14. The frame is also provided in the portion disposed below said recess 16 with a cylindrical arbor receiving seat 18, the longitudinal axis of which is substantially parallel to the axis of the barrel 14. Said arbor seat opens outward of the forward end of said frame.

A crane 20 is connected at its lower end to a crane arbor 22, said crane arbor and crane being preferably integrally connected. The crane arbor 22 is rotatably mounted within the arbor seat

18 of the frame to permit movement of the upper or free end of the crane between the operative and inoperative positions thereof respectively illustrated in Figs. 2 and 3. In the operative position of Fig. 2, one face of the crane is juxtaposed to one side of the frame. A cylinder arbor 24 is also connected to the crane 20 at the upper end thereof for rotatably supporting a cylinder 26. The cylinder is provided with the conventional cartridge holding chambers 28.

The crane 20 and cylinder arbor 24 are provided with a bearing 30 extending longitudinally of said arbor, said bearing slidably receiving a conventional ejector rod 32 which serves to eject cartridges or empty shells from the cylinder 15 chambers 28.

A cylinder lock or latch 34 is slidably mounted with respect to the frame 10 for purposes of detachably securing the rear end of the cylinder in its operative or firing position illustrated in Figs. 1 and 2. In conventional revolvers of the type described, when the cylinder latch 34 is moved rearward, the cylinder may then be moved out of the recess 16 as the crane 20 incidentally rotates with the arbor 22 about its axis.

Also in conventional revolvers, the upper or free end of the crane is not secured in operative or firing position other than by means of the latch 34 securing the cylinder and cylinder arbor 24 in operative position. Since the arbor 24 is carried by the crane, the crane will be satisfactorily maintained in operative position under normal conditions of use. However, should the exposed left side of the cylinder, as viewed in Fig. 2, be subjected to a sufficiently hard blow such as when, for example, the revolver is accidentally dropped, inasmuch as the rearward end of the cylinder is locked against movement by latch 34, the upper end of the crane will be moved by the blow to the right, as viewed in Fig. 2, and may possibly be sprung from its normal shape and become distorted, thus producing a consequent misalignment of the cylinder arbor 24 with the crane arbor 22. Such misalignment of the cylinder arbor will serve to prevent proper alignment of the cartridge chambers 28 with the bore of the barrel.

In order that accidents similar to that described will not distort the crane and cylinder arbor, the revolver is provided with a crane latch and operating mechanism therefor comprising the present invention, details of which will now be described. The face of the crane 20, which is normally disposed in juxtaposition to one side of the forward portion of the frame, is provided with a channel 36 which extends longitudinally of the crane, from one end to the other, and transverse to the axis of the cylinder when mounted on the cylinder arbor of the crane. The side walls defining the channel 36 are respectively provided with guide grooves 38 and 40 opening into said channel, said grooves extending inward from the free end of the crane.

The channel 36 slidably receives a crane latch 42 which is provided at one end with a latching detent 44 and at one side of the other end with a protuberance 46 having an arcuate exterior surface substantially conforming to the curvature of the pivoted end portion of the crane and the adjoining portion of the crane arbor. However, said protuberance has a slightly smaller radius than said curvature of said crane and arbor portions to provide a clearance space 47, as indicated in Figs. 2 and 3, adapted to permit reciprocation of the latch inward of the crane 20 when the

latch is operatively mounted in the channel 36. The opposite edges of the crane latch are respectively provided with guide ribs 48 and 50 which are respectively slidably received in grooves 38 and 40 of the crane, said grooves preventing movement of the latch in a lateral direction with respect to the crane. The end of the crane latch opposite the detent 44 is provided in the face opposite the protuberance 46 with a cam slot or groove 52 which extends at an angle of substantially 45° to the longitudinal axis of the crane latch. The purpose of the cam groove 52 will be presently described. The crane latch is also provided with a laterally extending abutment or shoulder 54 adjacent the detent 44, the purposes of said shoulder being described hereinafter.

The crane arbor 22 and crane 20 are provided with a cylindrical seat 56 which extends longitudinally of the arbor 22 and opens outward of the crane end of the arbor. Said seat slidably receives a substantially cylindrical plunger 58 which is provided with a cylindrical recess 60 at one end and a manually engageable member or finger button 62 at the other end. One side of said plunger 58 is partially cut away to define a laterally extending cam 64 disposed at an angle of substantially 45° to the longitudinal axis of the plunger and adapted to be slidably received in and coact with cam groove 52 disposed in crane latch 42.

When the plunger 58 is operatively mounted in the seat 56, a coil spring 66 is disposed between the inner end of the seat 56 and the inner end of the cylindrical cavity 60 of the plunger and normally serves to bias the plunger outward of the seat 56.

In order that the movement of the crane latch outward of the channel 36 may be limited to the desired extent only, the crane is provided with a cylindrical opening 68 extending parallel to and adjacent the bearing 30, said opening receiving a cylindrical pin 70 adapted to engage the shoulder 54 of the crane latch when the detent 44 of said latch reaches its outermost position. The detent 44 of crane latch 42 is received in latch receiving notch 72 illustrated in Figs. 2 and 3, said notch being provided in the surface of the frame juxtaposed to the free end of the crane when the crane is disposed in the operative position with respect to said frame and as shown in Fig. 2. Movement of the crane latch inward of the free end of the crane is limited by engagement of the end of protuberance 46 with the wall of arbor seat 18 in the frame.

When the finger button 62 is manually actuated to move the plunger 58 inward of the crane and crane arbor, the cam 64 will coact with cam groove 52 to move the latch detent 44 out of the notch 72 and inward of the free end of the crane. Such inward movement of the crane latch will be sufficient to completely remove the detent 44 from the notch 72, whereby the crane may then be moved laterally from the position shown in Fig. 2 to that shown in Fig. 3, such movement of the crane also serving to remove the cylinder from the recess 16 in the frame.

During the inward movement of the plunger 58, the spring 66 is compressed. Upon release of the button 62, spring 66 will bias the plunger outward, such movement simultaneously causing the cam 64 to move the detent 44 of the crane latch outward of the free end of the crane. It will thus be seen that the spring 66 not only serves to bias the plunger 58 but, due to the coaction

between cam 64 and cam groove 52, said spring also normally biases the crane latch outward of the free end of the crane.

When the crane and cylinder are being moved from the position indicated in Fig. 3 to the operative position shown in Fig. 2, the detent 44 of the crane latch will first engage a portion of the surface of the frame indicated 14 in Figs. 2 and 3. Inasmuch as said portion 14 of said frame surface which is first engaged by the crane latch detent is disposed at an angle suitable to serve as a camming surface to bias said detent inward of the crane, continued inward movement of the crane toward the frame after initial contact between said frame and detent will serve to cam the crane latch detent 44 inward of the free end of the crane until such time as said detent reaches notch 72 in the frame, following which, spring 66 through the medium of plunger 58, cam 64, cam groove 52 and crane latch 42 will serve to dispose the outer end of detent 44 within the notch 72 to disengageably secure the crane in proper juxtaposition to the frame.

It will thus be seen that the mounting means for the cylinder, comprising the crane 20 and cylinder arbor 24 will hold the cylinder in operative position due to the crane latch 42 and the cylinder latch 34 which are respectively disposed at opposite ends of the cylinder. Therefore, if the revolver is dropped so that the exposed surface of the cylinder opposite the crane and referred to above is subjected even to a blow of great force, the cylinder latch 34 and particularly the crane latch 42 will serve to prevent dislodgment of the cylinder from its operative position and will further and especially prevent any distortion of the crane 20 or the cylinder arbor 24.

It will also be observed that when the crane is latched in the operative position indicated in Figs. 1 and 2, the only exposed portion of the crane latch or its actuating mechanism comprises the manually engageable finger button 62 and the portion of the plunger 58 immediately adjacent thereto. None of said exposed portions have any grooves or crevices in which dirt or other extraneous matter may accumulate and therefore the operation of the crane latch and its actuating mechanism will not be fouled at any time due to such accumulations.

It will further be observed that the engagement of the pin 70 with the shoulder 54 of the crane latch will serve to prevent any frictional engagement between the crane latch and the ejector rod 32, whereby free rotation of the cylinder and the ejector rod with respect to the cylinder arbor 24 may take place for any purposes desired.

The present invention thus provides a crane lock mechanism essentially comprising a latch which is completely enclosed within the firearm when the crane is disposed in operative position and the actuating mechanism for the crane latch is also completely enclosed except for a manually engageable member comprising a finger button having a rounded surface and projecting only slightly forward of the forward end of the frame. Said button is disposed in a position on the frame wherein it will not offer objectionable obstruction during use of the revolver or while placing the revolver in a holster. Furthermore, the crane latch may be disengaged from its latching position by a slight movement of the manually engageable member inward of the revolver.

Still further, when the crane and cylinder are being moved from inoperative to operative position, the construction is such that the crane latch will be automatically cammed inward and then moved outward into engagement with the notch in the frame which receives the outward projecting latching detent of the crane latch.

In the foregoing, descriptive terms used to denote location such as forward, rearward, and the like have been used while considering the end of the frame from which the barrel projects the front or forward end and the end of the frame from which the handle projects the rearward end. Said descriptive terms are to be considered in the same relative sense with respect to the revolver, regardless of the position in which the revolver may ultimately be disposed.

While the invention has been illustrated and described in its preferred embodiment and has included certain details, it should be understood that the invention is not to be limited to the precise details herein illustrated and described nor to use with the exact revolver described herein since the invention may be embodied in other firearms having a pivoted crane and said invention may also be carried out in other ways, falling within the scope of the invention as claimed.

What I claim is:

1. In a revolver, the combination of a frame, a cylinder, a crane pivotally carried by said frame, one end of said crane rotatably supporting said cylinder and also adapted to be moved laterally from said frame, a cylinder latch adapted to detachably retain said cylinder in operative position with respect to said frame, and a crane latch slidably carried by said crane and reciprocable in a direction transverse to the axis of said cylinder, said latch being adapted to engage said frame to detachably secure said crane in operative position with respect to said frame when the cylinder is disposed in said operative position.

2. In a revolver, the combination of a frame provided with latch engaging means, a cylinder, a crane pivotally carried by said frame, one end of said crane rotatably supporting said cylinder and also adapted to be moved laterally from said frame, a cylinder latch adapted to detachably retain said cylinder in operative position with respect to said frame, and a crane latch slidably carried by said crane and reciprocable in a direction transverse to the axis of said cylinder, said latch being adapted to engage said latch engaging means on said frame to detachably secure said crane in operative position with respect to said frame when the cylinder is disposed in said operative position.

3. In a revolver, the combination of a frame having latch engaging means, a cylinder, a crane pivotally connected at one end of said frame and adapted to have its free end pivotally moved laterally therefrom, said crane adjacent its free end rotatably supporting said cylinder, a cylinder latch adapted to detachably retain said cylinder in operative position with respect to said frame, and a crane latch slidably carried by said crane and reciprocable in a direction transverse to the axis of said cylinder, said latch being adapted to project beyond the free end of said crane and engage said latch engaging means of said frame to detachably secure said crane in operative position with respect to said frame when the cylinder is disposed in said operative position.

4. In a revolver, the combination of a frame having latch engaging means, a cylinder, a crane pivotally connected at one end to said frame and adapted to have its free end pivotally moved laterally therefrom, said crane adjacent its free end rotatably supporting said cylinder, a cylinder latch adapted to detachably retain said cylinder in operative position with respect to said frame, a crane latch slidably carried by said crane and reciprocable in a direction transverse to the axis of said cylinder, said latch being adapted to project beyond the free end of said crane and engage said frame latch engaging means of said frame to detachably secure said crane in operative position with respect to said frame when the cylinder is disposed in said operative position, and means adapted to coact with said crane latch to limit the movement thereof outward of the free end of said crane.

5. In a revolver, the combination of a frame having latch engaging means, a crane pivotally connected at one end to said frame and adapted to be juxtaposed to said frame in operative position, the side of the crane which is adapted to be juxtaposed to said frame being provided with a channel extending longitudinally of said crane and transversely to the pivotal axis thereof, a cylinder rotatably supported by said crane adjacent the free end thereon, said free end of the crane being opposite its pivoted end and adapted to be pivotally moved laterally from the frame, a cylinder latch adapted to detachably retain said cylinder in operative position with respect to the frame, and a crane latch slidably carried by said crane in the channel therein, said crane latch being movable longitudinally of said channel and having one end adapted to project beyond the free end of said crane and engage said latch engaging means of said frame to detachably secure said crane in operative position with respect to said frame when the cylinder is disposed in said operative position.

6. In a revolver, the combination of a frame having latch engaging means, a crane pivotally connected at one end to said frame, a cylinder rotatably supported by said crane adjacent the free end thereof, said free end of the crane being adapted to be pivotally moved laterally from the frame, a cylinder latch adapted to detachably retain said cylinder in operative position with respect to the frame, a crane latch slidably carried by said crane and adapted to project beyond the free end of said crane and engage said latch engaging means of said frame to detachably secure said crane in operative position with respect to said frame when the cylinder is disposed in said operative position, means movably carried by said crane, and a cam carried by said last mentioned means and adapted to be moved therewith to disengage said crane latch from said latch engaging means of said frame to permit movement of said cylinder and the free end of said crane from said operative positions thereof.

7. In a revolver, the combination of a frame having latch engaging means, a crane pivotally connected at one end to said frame, a cylinder rotatably supported by said crane adjacent the free end thereof, said free end of the crane being adapted to be pivotally moved laterally from the frame, a cylinder latch adapted to detachably retain said cylinder in operative position with respect to the frame, a crane latch slidably carried by said crane and adapted to project beyond the free end of said crane and engage said latch

engaging means of said frame to detachably secure said crane in operative position with respect to said frame when the cylinder is disposed in said operative position, means slidably carried by said crane and provided with a manually engageable portion projecting outward of said crane, and a cam carried by said last mentioned means and adapted to be moved therewith when actuated by said manually engageable portion to disengage said crane latch from said latch engaging means of said frame to permit movement of said cylinder and the free end of said crane from said operative positions thereof.

8. In combination in a revolver, a frame provided with an arbor seat, said frame also being provided with latch engaging means, an arbor pivotally mounted in the arbor seat of said frame, a crane connected at one end to and pivotally movable with said arbor, said arbor and crane containing a seat opening outward of said crane and in substantial co-axial alignment with said arbor, a cylinder pivotally supported by said crane, a cylinder latch adapted to detachably retain said cylinder in operative position with respect to said frame, a crane latch slidably carried by said crane and reciprocable in a direction extending transversely to the axis of said cylinder, said crane latch being adapted to engage said latch engaging means on said frame to detachably secure said crane in operative position with respect to said frame, and means mounted for slidable movement in said seat in said arbor and crane and engageable with said crane latch to disengage it from said latch engaging means of said frame to permit movement of said crane and cylinder from said operative positions thereof.

9. In combination in a revolver, a frame provided with an arbor seat, said frame also being provided with latch engaging means, an arbor pivotally mounted in the arbor seat of said frame, a crane connected at one end to and pivotally movable with said arbor, said arbor and crane containing a seat opening outward of said crane, a cylinder pivotally supported by said crane, a cylinder latch adapted to detachably retain said cylinder in operative position with respect to said frame, a crane latch slidably carried by said crane and reciprocable in a path extending transversely to the axis of said cylinder, said crane latch being adapted to engage said latch engaging means on said frame to detachably secure said crane in operative position with respect to said frame, means slidably movable in said seat in said arbor and crane, and a cam and cam groove disposed one on said slidable means and the other on said crane latch and adapted to coact to disengage said crane latch from said latch engaging means of said frame when said slidable means is moved to permit movement of said crane and cylinder from said operative positions thereof.

10. In combination in a revolver, a frame provided with an arbor seat, said frame also being provided with latch engaging means, an arbor pivotally mounted in the arbor seat of said frame, a crane connected at one end to and pivotally movable with said arbor to and from the operative position of the crane with respect to the frame, said arbor and crane containing a seat opening outward of said crane and said crane also having a channel which is concealed when the crane is in said operative position, a cylinder pivotally supported by said crane, a cylinder latch

adapted to detachably retain said cylinder in operative position with respect to said frame, a crane latch slidably carried by said channel in said crane and reciprocable therein in a path extending transverse to the axis of said cylinder, said crane latch being adapted to project beyond the free end of said crane and engage said latch engaging means on said frame to detachably secure said crane in operative position with respect to said frame, means movably mounted in said seat in said arbor and crane and adapted to coact with said crane latch to disengage it from said

latch engaging means of said frame to permit movement of said crane and cylinder from said operative positions thereof, and a manually engageable member connected to said last mentioned means to effect movement of said means in said seat therefor, said member projecting outward of said crane and comprising the only appreciably exposed portion of said crane latch and the actuating means therefor when the crane 10 is disposed in operative position.

WILLIAM L. SWARTZ.
